(57) **CLAIM**

The ornamental design for a drinking bottle, as shown and described.

DESCRIPTION

FIG. 1 is a perspective view of a drinking bottle, according to the present design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a perspective view of the drinking bottle in an open configuration thereof.

The broken lines in the drawings illustrate portions of the drinking bottle that form no part of the claimed design.
